UNITED STATES PATENT OFFICE.

RALPH BROWNSON, OF HASTINGS, MINNESOTA.

CAN OPENER.

Application filed July 26, 1923. Serial No. 653,940.

To all whom it may concern:

Be it known that I, RALPH BROWNSON, a citizen of the United States, residing at Hastings, in the county of Dakota and State 5 of Minnesota, have invented certain new and useful Improvements in Can Openers, of which the following is a specification.

My invention relates to improvements in can openers, and has for one of its objects to 10 provide a can opener by which a clean cut opening may be effected, and which will be cheap of construction and simple of operation, and involving novel features of construction, whereby the head of the can may 15 be approximately wholly removed and at the same time be controlled to prevent irregular buckling out of its normal flat state in a can opening operation, including the 20 final severing cut, so that the removed head will resemble a flat plate with a slightly crimped surrounding edge, and leave a smooth, unbroken edge in the throat of the can.

A further object of the invention is the 25 provision of improved means in a can opener for opening cans having inset or recessed heads, whereby, in the process of cutting out the latter, the same is simultaneously progressively severed from the body of the can 30 and controlled to retain its original position at points located adjacent the point of severance.

Other objects and advantages of my invention will be pointed out as this specification progresses, the invention consisting 35 in the construction, combination, and arrangement of parts hereinafter set forth and claimed.

In the accompanying drawings, forming 40 part of this specification:

Figure 1, is a view of a can opener embodying my invention.

Figure 2, is a side view of same.

Figure 3, is a fragmentary perspective 45 view of a can opener showing it in the position it assumed on the can in the process of opening the latter.

Figure 4, is a sectional view on line 4—4 of Figure 3.

Figure 5, is an outline view of the cutting 50 end of my improved opener, showing the can in cross section.

Figure 6, is a vertical sectional view of a fragment of the can, illustrating the man-

ner of cut made by my improved can opener; and

Figures 7 and 8, are perspective views of fragments of a can, illustrating, respectively, a can opened with an ordinary opener, and the removed top of a can opened with 60 applicant's improved device.

In the drawings, A designates a can, a the head thereof, and b, what may be termed the rolled rim thereof. The rim is here shown as being of double thickness, but may be of 65 any conventional form, it not being thought important to describe the same.

The invention comprises a handle 1, a cutting blade 2 having cutting edges 3—3, an outer guide member 4 for guiding the blade, 70 extending parallel with the blade 2, and an inner lug or shoulder 5. Forming the crotch between the blade and the guide member, is a fulcrum block 6. The handle 1 is formed, preferably, of a metal strip of uniform 75 width and thickness, bent intermediate its ends to form two forwardly diverging handle members 7 and 8, the latter of these being bent to extend for a short distance in parallelism with the member 7, then outwardly and upwardly to form the shoulder 5, the member 8 terminating an appreciable distance short of the member 7.

The blade 2 and fulcrum block 6 are equal in width to that of the handle, to be flush 85 with the sides thereof, and are positioned in superposed relation between the members 7 and 8 to extend longitudinally thereof. The blade and fulcrum lever are firmly secured between the members 7 and 8, as by means of 90 suitable rivets, designated at 9. The parts of the device are so relatively positioned as to bring the outer extremity of the blade guide member 4, slightly in advance of the point 10 of the blade 2, the cutting edges 8 95 of the latter converging in a curve symmetrically toward the point 10.

The forward face 11 of the fulcrum block 6, extends at right angles to the parallel edges and the inner face of the member 7, 100 and is suitably hardened, as by tempering, to enable it to indent, by means of its corners 12, the metal of the can, to avoid slipping during a can opening operation.

The block, which may be termed the end 105 of the handle, is of uniform thickness to bring the blade and guide member 4 into parallelism when they are in their assembled

state, and hold them suitably close to the outer wall thereof. The forward face 13 of the shoulder or extension 5, is disposed at an obtuse angle to the flat outer side of the 5 blade 2, and is located an appreciable distance in advance of the face 11 of the fulcrum block, for a purpose to be hereinafter explained.

The shoulder member or lug 5 has an ar- 10 cuate or curved outer edge 14, whereby, owing to its angularity with the blade 2, or, in other words, its dip toward the can head, it will be enabled to roll with its outer lower edge upon the top of the can, said top being 15 shown inset or recessed from the top edge 15 of the can. This is best illustrated in Figure 4 of the drawings, wherein the blade is shown thrust through the top of the can, one of the corners 12 of the fulcrum block 20 being shown in engagement with the edge 15 thereof, while, at the same time, the edge 14 of the lug 5 is in rolling engagement with the top 15 of the can.

Obviously, an oscillatory movement of the 25 handle to the right about the point 12, as indicated by the arrow in Figure 4, will effect an extension at *c* of the cut in the head of the can and simultaneously, a rolling movement of the edge 14 upon the latter, thereby preventing the head from buckling 30 upward by the upwardly directed forces applied by the cutting edge of the blade.

By inclining the lug 5 toward the blade (Figure 5) and disposing it bodily in advance of the face 11 of the fulcrum block, I secure a clearance at 16, which clearance is adapted to receive the fin or flange 17, formed by the cutting action of the blade from below upward. As the severing cut is 40 located relatively close to the rolled rim *b* of the can (as shown in Figure 6), a very small fin is formed by the action of the blade. Obviously, during a cutting movement, the head of the can is initially held 45 down against vertical displacement at the point 18 (Figure 4), which point is coincident with the long axis of the blade designated by the line 19—19, the distance between the point 18 and the point *c* on the cutting edge of the blade being approxi- 50 mately only half the width of the blade, thus reducing the span of metal at this point, and preventing extensive upward buckling of the metal, as distinguished from ordinary cutters not having a member corresponding to the lug 5, but having a shoulder as indicated by dotted lines at 20 in Figure 5, which shoulder is approximately on the level 55 with the top edge 15 of the can, thus enabling the formation of long creases radiating toward the center of the can and extensive upward buckling of the metal in a can opening movement of the can, as shown in Figure 7. Also, as the opening operation progresses around the edge of the can, the

head of the can ordinarily dishes materially, frequently coming in contact with the user's fingers. This is a common occurrence in the use of ordinary can openers, especially in cans having sunken or recessed heads. 70

In Figure 8, I have shown the head of a can removed by my improved opener, it being shown to have retained its flat original state, excepting the small surrounding fin 17. 75

As shown in Figures 3 and 5, the blade guide 4 is adapted to engage the outside of the can to prevent the blade from slipping, as the user projects it through the head of the can. Applicant is aware of the fact, 80 that there are can openers in use having guides of this type, and nothing is herein claimed for this feature, but as far as applicant knows, no can opener exists having members to control the can head in the manner described. As an article of manufacture, applicant's construction involves certain novel features which renders its manufacture extremely cheap and simple, the 85 handle 1 being preferably made of a single piece of material of uniform width and thickness, as hereinbefore described, to form both the guide member 4 and the shoulder 5. By superposing the blade on the fulcrum block, and securing the same by means of the 90 rivets 9 between the members 7 and 8, I 95 secure a strong, neat, and durable construction.

In operation, the point of the blade is placed close to the inside of the rim *b* of the 100 can, or the edge thereof, as the case may be, to bring the blade guide against the outside of the can, to function as a gauge during the can opening process, and at the same time as a guard against slipping off the can top. 105 The opener is then thrust through the top of the can until the face 11 of the fulcrum block impinges upon the rim *b* of the can. The opener is now rocked about either of the 110 edges 12, as the case may be, and is then moved step by step progressively with each 115 rocking movement of the opener until the top of the can is completely severed. The lug 5 throughout the process prevents the 120 head from being pulled upward by the cutting action (from below upward) of the blade. Thus, by having the lug in engagement with the head of the can at a point located between the cutting edges of the 125 blade throughout the process, cutting of the blade is facilitated, as distinguished from blades not having the lug 5 wherein, during a cutting movement, the metal head bends upward, frequently creasing from points located near the center of the can, and tending to pinch and retard the blade in its movement.

I claim:

1. In a can opener, the combination of a handle, a blade guide on one side of the 130

lower portion of said handle, a cutting blade terminating short of said blade guide, and being spaced laterally therefrom to form a crotch therebetween, and a downwardly facing shoulder on the outside of said blade, located in advance of the bottom of said crotch.

2. In a can opener, a handle having a flat, hardened end rectangular in cross section, 10 and transversely spaced guide and blade members extending outwardly from opposite sides of said hardened end, a shoulder on the outside of said blade member facing toward the end of the latter and extending 15 at an obtuse angle from the outer face thereof.

3. In a can opener, a looped strip of metal to form a handle therefor, one end extending a greater distance from the looped portion than the other end thereof, means comprising a cutting blade and a hardened member having oppositely disposed angular portions thereon inserted intermediate the ends of said handle, means to integrally connect the handle and said inserted means, 20 and a shoulder formed adjacent the blade by bending the short end of said handle to extend outwardly and downwardly from said blade, for the purpose set forth.

In testimony whereof I affix my signature.

RALPH BROWNSON.
